(57) **CLAIM**

The ornamental design for a combined light and electromagnetic radiation device, as shown and described.

DESCRIPTION

FIG. 1 is a top front left perspective view of a combined light and electromagnetic radiation device, showing our new design;

FIG. 2 is a top front right perspective view thereof;

FIG. 3 is a top rear right perspective view thereof;

FIG. 4 is a top rear left perspective view thereof;

FIG. 5 is a bottom front left perspective view thereof;

FIG. 6 is a bottom front right perspective view thereof;

FIG. 7 is a bottom rear right perspective view thereof;

FIG. 8 is a bottom rear left perspective view thereof;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The diagonal dashed shade lines represent transparent components. The relatively small broken lines depict unclaimed portions of the combined light and electromagnetic radiation device, and the relatively small broken lines form no part of the claimed design.
